DAMPER DEVICE

Fred D. Hoffman, Cleveland, Ohio

Application June 29, 1938, Serial No. 216,498

4 Claims. (Cl. 126—293)

This invention relates to a damper device for use in connection with furnaces and particularly to a check damper operatively associated with the furnace exhaust flue so as to reduce the flue temperature, to effect better combustion of the fuel with a consequent reduction of smoke.

A more specific object is to provide a damper which admits outside air through the exhaust flue in such a manner that it retards the discharge of the gases from the fire pot and assures more nearly complete combustion thereof prior to the passage of the gases into the furnace stack and which causes a large percentage of the air so admitted to pass beyond the stack and enter the fire pot of the furnace to assist in sustaining combustion of the gases evolved therein.

Another specific object is to deflect the air so admitted in a manner to produce a swirling motion of the resultant air stream flowing into the fire pot.

Other objects and advantages will become apparent from the following specification wherein reference is made to the drawings, in which:

Fig. 1 is a side elevation of a domestic hot air furnace with the device of the present invention installed thereon;

Fig. 2 is an enlarged outer end elevation of the damper device of the present invention as viewed from the right in Fig. 1;

Fig. 3 is a sectional view of the damper device and a part of the exhaust flue and is taken on a plane indicated by the line 3—3 in Fig. 2;

Fig. 4 is an elevation, partly in section, of the adjustable element of the damper device viewed from the inside of the furnace flue, as indicated by the line 4—4 in Fig. 3; and

Figs. 5, 6 and 7 are fragmentary sectional views taken on planes indicated by the lines 5—5, 6—6 and 7—7, respectively, in Fig. 4.

Referring to the drawings, the furnace comprises a fire pot 1 spanned at the bottom by the usual grate bars (not shown) and having therebeneath the usual ash pit into which air is admitted through a damper 2 for sustaining combustion. Surmounting the fire pot 1 is the customary large radiating head or radiatori 3 which is connected to the usual horizontally extending exhaust flue 4, the flue in turn being connected to an upwardly extending stack 5. The exhaust flue 4 has a portion providing an extension 6 which extends beyond the stack 5, the extension 6 being open at its outer end. The damper device of the present invention, designated generally at 10, is installed on the outer end of the extended portion of the exhaust flue, and, as better illus-

trated in Figs. 2 and 3, comprises a cast iron annular header or collar 11 which is snugly fitted onto the end flue extension 6. Hingedly connected by a suitable pin 12 to suitable lugs on the upper edge of the header 11 is the damper cover plate 13. The cover plate 13 normally closes the open end of the flue, as illustrated, but is provided with a plurality of openings 14 in the form of circular sectors uniformly distributed about the center of the plate 13. The plate 13 is provided with a central hub 15 in which is received a suitable shaft 16 which extends coaxially of the plate 13. The shaft 16 has a threaded portion engaging internal threads in the hub 15 so that it may be adjusted axially, a locking nut 17 being provided for locking the shaft in the desired adjusted position. Rotatably mounted on the shaft 16 is a rotatable damper 18 which has a plurality of openings 19 corresponding in size and shape to and arranged for registry with the openings 14 of the damper plate 13. The damper 18 is rotatable about the shaft 16 and, for illustration only, the rotation may be effected by a bi-metal thermostatic coil 20, one end of which is secured to the shaft 16 by a suitable screw 21 and the other end of which is secured to a hub portion 22 on the damper 18. The thermostatic coil 20 can be so arranged that when unheated, it rotates the damper 18 to a position wherein the openings 19 are out of registry with the openings 14 and the admission of air is substantially stopped. When the coil 20 is heated, it rotates the damper plate to bring the openings 19 gradually into registry with the openings 14 for admitting air, variations in the amount of air admitted being effected between the extreme positions. Suitable stops are provided on the damper 18 and engage a suitable stopping lug 24 on the plate 13 for limiting the movement of the rotatable damper 18 from a position in which the openings 14 are entirely blocked to a position in which they are in full registry with the openings 19.

No claim is made herein to the thermostatic adjustment above described of the damper device 18, etc., as shown in Fig. 3.

As illustrated, the axis of the shaft 16 slopes downwardly toward the fire pot so that air entering through the registering part of the openings 14 and 19 tends to flow downwardly through the extension 6 and flue 4. With the structure thus far described, the air admitted would tend to flow downwardly into the flue extension and toward the radiating hood 3 of the furnace, but due to the upward pull of the stack 5, and par-

tial heating of the admitted air, this air would soon lose its inward velocity and movement toward the radiating hood 3 and rise and partially return and flow out through the stack 5 so that substantially none of the air admitted would reach the furnace.

It is desirable, however, to admit air entirely into the furnace through the exhaust flue while the fire is in check in order to sustain combustion of the fuel and evolve the gases while the damper 2 is fully or partially closed. Further, it is desirable to retard the escape of unburned gases through the stack 5. In order to insure the passage of the air entirely into the radiating hood 3 of the furnace, a plurality of baffle vanes 25 are provided on the rotatable damper 18 in alignment with the openings 19.

As better illustrated in Figs. 5 to 7, inclusive, each baffle vane 25 is substantially coextensive with and aligned with the projected area of the associated opening 19. Likewise, each baffle 25 is concave toward the associated opening 19 and beginning at the plane of the outer face of the damper 18 at one edge of its opening 19, slopes inwardly on a gradual curve and terminates substantially in alignment with the opposite edge of its opening 19 a short distance behind the plane of the outer face of the plate 18. The wall of the baffle at its discharge edge, indicated at 26, is substantially parallel to the plane of the outer face of the damper 18. The curve and length of the baffle in the direction of flow of air therealong is decrescent from the periphery of the damper 18 toward the axis thereof. Furthermore, each baffle 25 has a peripheral wall 27 so that all air entering any one of the passages 19 is constrained to flow along the baffle 25 and be discharged inwardly from the damper 18 as a spiral stream swirling about the extended axis of the damper 18. By virtue of the swirling motion imparted to the air admitted through the damper device 10, the induced air travels a much greater distance longitudinally of the flue and does not tend to reverse and by-pass through the stack 5. On the contrary, it appears that the action is as follows: the stream of air from the baffles 25 is deflected downwardly by the outgoing heated products of combustion from the fire pot as the products rise and follow along the upper wall portion of the flue 4. A considerable amount of unburned gases also tends to escape but is relatively unheated and tends to lie in strata below the hot products. These unburned gases become mixed with the admitted air though the hotter products of combustion may escape through the flue. This compression of the area of the swirling stream of air by the escaping products does not appear to retard its flow, and a large amount of such air enters the hood 3 wherein, being somewhat heated, mixes with the unburned gases which are then ignited and consumed in the hood 3. In order to render the rotation of the damper 18 easily rotatable, it may be spaced slightly from the cover plate 13 by a washer 28. Due to this spacing, a slight seepage of air past the damper may be permitted at all times.

On the usual hot air domestic furnace, it has been found that by the use of the present device the flue temperature, which normally reaches about 560 degrees F., is maintained at less than 275 degrees F. by the present damper device and

that the efficiency of the furnace is raised from a normal efficiency of 37% to an efficiency of 60.8%. Furthermore, the usual amount of smoke discharged from the stack is reduced very noticeably and the heat supplied from the furnace is rendered much more uniform and the fire maintained for longer periods with a considerable reduction in the amount of fuel supplied and the attendance required for the furnace.

Having thus described my invention, I claim: 10

1. A check damper device for a furnace having a substantially horizontal exhaust flue open at its outer end and connected at its inner end with the furnace and having an upwardly directed stack between its ends, said damper device comprising a plurality of openings adapted to admit outside air into the open end of said flue, and means respective to said openings and positioned directly adjacent thereto and inclined relative to the normal paths of air into said openings in a manner to cause said air to flow as a spiral swirling stream from the open end of the flue into the furnace.

2. A check damper device for a furnace having a substantially horizontal exhaust flue open at its outer end and an upright stack connected to the flue between the open end and the furnace, and comprising a member normally closing the open end of the flue and having openings for admitting outside air into the flue, an adjustable damper cooperable with said member for opening and closing said openings to control the volume of air admitted therewith, and means carried by said damper for deflecting the admitted air as an annular swirling stream directed along the flue toward the furnace.

3. A check damper device for a furnace having a substantially horizontal exhaust flue open at its outer end, and an upright stack connected to the flue between the open end and the furnace, and comprising a collar received on and snugly fitting the open end of the flue, a cover plate hingedly connected thereto and normally overlying the open end of the flue and having openings for admitting outside air into the flue, a rotatable damper mounted on said plate in substantially face to face relation to the inner face thereof and cooperable with said openings for controlling the volume admitted therethrough, and deflecting vanes on said damper and shaped for deflecting the admitted air as an annular swirling stream directed along the flue toward the furnace.

4. A check damper for a furnace having a substantially horizontal exhaust flue open at its outer end and connected at its other end to the furnace, and an upright stack connected to the flue between the open end and the furnace, and comprising a cover plate normally closing the open end of the flue and having a plurality of openings therein, a rotatable damper coaxial therewith and having openings arranged for registry with and offset relation to the openings of the cover plate, baffles on the rotatable damper and aligned with the openings therein, respectively, said baffles being curved in cross section and concave toward the apertures and extending from the plane of the damper inwardly for deflecting the air entering the apertures spirally along the flue.

FRED D. HOFFMAN.
